Specification for Design.

Patented Sept. 28, 1915.

Application filed April 15, 1915. Serial No. 21,616. Term of patent 14 years.

To all whom it may concern:

Be it known that I, LLOYD D. FREELAND, a citizen of the United States, residing at Chicago, in the county of Cook and State of Illinois, have invented a new, original, and ornamental Design for Frames for Engine-Driven Fans, of which the following is a specification, reference being had to the accompanying drawing, forming part thereof.

Figure 1 is a side elevation of a frame for an engine-driven fan, showing my new design. Fig. 2 is a front elevation thereof.

I claim:

The ornamental design for a frame for an engine-driven fan, as shown.

LLOYD D. FREELAND.
